UNITED STATES PATENT OFFICE.

FELIX KOCH, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

CAR-TRUCK.

1,203,360.

Specification of Letters Patent. Patented Oct. 31, 1916.

Application filed December 29, 1915. Serial No. 69,183.

To all whom it may concern:

Be it known that I, FELIX KOCH, a citizen of the United States, residing at No. 62 North Harrison avenue, Bellevue, in the 5 county of Allegheny and State of Pennsylvania, have invented certain new and useful Improvements in Car-Trucks, of which the following is a specification.

An object of the present invention is to 10 provide improvements in what is known to railway engineers as the "Fox" type of truck for railway rolling stock, or in trucks of similar type, and particularly to increase the strength of the truck without increasing 15 its size or materially changing its proportions.

Railway cars have increased in capacity from, say 60,000 lbs. in 1900 to 120,000 lbs. or more, in 1915, but little attention has 20 been given to the strengthening of the "Fox" type of truck, the same having been used practically without change in construction notwithstanding such increase in car capacity, one of the reasons therefor being that 25 the side frames of these trucks are formed by pressing sheet metal to shape in expensive dies and an increase in the size or proportions of such trucks would render such dies useless.

30 An example of the "Fox" type of freight car truck is illustrated in United States Patent No. 468,146, granted to D. L. Barnes, February 2nd, 1892. An example of the "Fox" type of truck especially adapted for 35 locomotive tenders is found in United States Patent No. 505,159, granted to S. Fox, September 19th, 1893, both of these patents illustrating trucks in which the side frames are formed of pressed steel.

40 Trucks of the "Fox" type are constructed with rigid side frames which at their central portions support the transoms, the side frames transmitting the load from the transoms to the car axles through the medium 45 of U shaped pedestals formed at the ends of the rigid side frames, which pedestals receive and are supported by springs mounted on the axle journal boxes, the legs of said pedestals also forming bearings in which 50 the journal boxes slide vertically. Sometimes the side frames of "Fox" trucks are

built up of plates and commercial sections, an example of such built-up side frame being found in United States Patent No. 553,431, granted to C. T. Schoen, January 21st, 1896.

A specific object of the present invention is to strengthen the side frame of the "Fox" type of truck in such a manner as to adapt it for use in connection with railway rolling 60 stock of the increased capacity hereinbefore referred to without changing the contour of the truck frame or materially increasing the general dimensions and proportions of the truck.

65 This invention is illustrated and described in its adaptation for use as a freight car truck, but without special description it will be readily appreciated that the improvements are equally applicable to all trucks of 70 the "Fox" or similar type when adapted for use in connection with locomotive tenders. Only so much of the "Fox" truck will be described as is necessary to illustrate this particular invention, references being had to 75 the accompanying drawings in which like characters refer to like parts, and in which:

Figure 1 is a sectional side elevation of a "Fox" truck, Fig. 2 is a sectional plan view of the same, and Figs. 3 and 4 are vertical 80 sections taken on lines 3—3 and 4—4 respectively of Fig. 1. Figs. 5, 6 and 7 are sectional views taken on line 5—5 of Fig. 1, showing modifications of the construction of the upper portion of the side frame.

85 Referring now in detail to the drawings, 1 indicates the side frame of what is known as the "Fox" type of truck, this side frame being similar in contour to the side frames illustrated in the patents hereinbefore referred to. The plate forming the side frame 1 is bent inwardly along portions of its upper edge, and at its end edges in the manner shown at 2 in Fig. 4 of the drawings, and is also bent outwardly at points indicated 95 by 3, 3 in Figs. 1 and 2 of the drawings. To the inner side of the side frame 1 a second plate 4, which is of about the same dimensions as the side frame 1, but may differ in thickness, is secured, said plate 4 being 100 bent inwardly along portions of its upper edge, and at its end edges in the manner

shown at 5 in Fig. 4 of the drawings, and also bent inwardly toward the longitudinal center line of the truck at points indicated by 6, 6 in Figs. 1 and 2 of the drawings. 5 When the plates 1 and 4 are placed together it will be seen that the central portions 7 and 8 respectively contact with each other and may be secured together by rivets or other suitable means. It will also be apparent 10 that as the result of the bending of plates 1 and 4 in the manner above described, there will be a space 9 intervening between the end portions of said plates, said space being taken up and maintained in the pedestal 15 portion of the frame by projecting portions 10 on the pedestal members 11, which are secured in position between the frame members 1 and 4, by any suitable means.

The space intervening between the upper 20 edge portions and end edge portions is shown in Fig. 4 as being taken up and maintained by an auxiliary or re-inforcing member 12, which may be of angular, or any suitable section, and in Fig. 5 as of T section.

Fig. 6 shows a modification of the last described construction in which the edge portions of the frame plates 1 and 4 are bent toward each other a sufficient distance to 30 make contact between them, the re-inforcing member 13 of Z, or other suitable section is secured to said edge portions by rivets passing through the re-inforcing member and edge portions of the frame members.

Fig. 7 illustrates a further modification 35 in which the edge portions of frame plates 1 and 4 are spread farther apart or bent away from each other a sufficient distance to admit of the insertion therebetween of a re- 40 inforcing member 14, of channel or other suitable section; said member being secured in position by suitable means passing through the edge portions and re-inforcing member.

45 15 indicates the transoms or cross-tie members which serve to tie together the frame members 1 and 4 forming the opposite sides of the truck, these transom members being braced and stiffened by the usual 50 crossbrace members 16 and the center brace member 17.

18 indicates a gusset member adapted to assist in securing together and bracing the transom members 15, the side frame members 1 and 4, and the re-inforcing members, the gusset member being secured to the upper flange of the transom member 15, and to the flange of the re-inforcing member.

60 Further description of the essential parts of the "Fox" type of truck will be found in either of the aforementioned patents, and hence features which are not pertinent to the present invention are not described herein.

65 Having thus described the invention,

what I claim as new and desire to secure by Letters Patent is:

1. In a car truck, a side frame comprising a plurality of connected plates, the ends of said plates being spaced apart, a reinforcing member secured along the top and end edges of said plates, and a pedestal member secured between the spaced end portions of said plates. 70

2. In a car truck, a side frame comprising a plurality of connected plates, the ends of said plates being bent laterally of the side frame in opposite directions to form a recess, an angular member secured along the top edges of said plates, and a pedestal member extending between and secured to said plates within said recess. 80

3. In a car truck, a side frame comprising a plurality of connected plates, one of said plates being offset outwardly at its ends, 85 and the other of said plates being offset inwardly at its ends, a reinforcing member secured along the top and end edges of said plates, and pedestal members secured between the offset portions of said ends. 90

4. In a car truck, a side frame comprising a plurality of connected plates extending the full length of said truck, a pedestal member secured to said plates, said plates being offset laterally of the side frame to 95 form a recess for the reception of said pedestal member, and a reinforcing member secured to the top edges of said plates.

5. In a car truck, a side frame comprising a plurality of plates extending the full 100 length of said truck, and a reinforcing member secured along the top and end edge portions of said plates.

6. In a car truck, a side frame comprising a plurality of plates extending the full 105 length of said truck, portions of the ends of said plates being spaced apart, pedestals extending between and secured to said end portions, and a reinforcing member secured to the top and end edges of said plates. 110

7. In a car truck, a side frame composed of two plates, portions of said plates being secured together in contact with each other, the other portions being spaced apart, and an angular re-inforcing member inserted between and secured to said spaced apart portions, said member extending for the full length of said plates. 115

8. In a car truck, a side frame composed of two plates, portions of said plates being secured together in contact with each other, the other portions being spaced apart, a flanged re-inforcing member secured between said spaced apart portions, and a gusset plate secured to the flange of said re-inforcing member. 120

9. In a car truck, side frames, each composed of two plates, portions of said plates being secured together in contact with each other, the other portions being spaced apart, 130

a re-inforcing member secured between said spaced apart portions, transoms connecting the side frames, and gusset members connecting said re-inforcing members and 5 transoms.

10. In a car truck, a side frame comprising a plurality of plates extending the full length of said truck and having pedestal openings in their ends, said plates being offset 10 set around said openings, and pedestal members extending between and secured to said offset portions.

11. In a car truck, a side frame composed wholly of two plates, the end portions of 15 said plates being offset laterally of the truck in opposite directions, and pedestals extending between and secured to the offset portions of said plates.

12. In a car truck, a side frame comprising 20 a plurality of connected plates extending the full length of said truck, the end portions of said plates being offset laterally

of the truck in opposite directions, pedestals secured between the end portions of said plates, and a reinforcing member secured 25 along the top and end edges of said plates.

13. In a car truck, a side frame composed wholly of two plates, and a reinforcing member of angular form secured between the top and end edges of said plates. 30

14. In a car truck, side frames, each of said side frames composed wholly of two plates, a reinforcing member secured along the top and end edges of each of said side frames, transoms extending between and secured to said side frames, and gusset plates connecting said reinforcing member and transoms. 35

In testimony whereof I affix my signature in presence of two witnesses.

FELIX KOCH.
